ELECTRICAL TERMINAL

George Sylvester Reider, Jr., Highspire, Pa., assignor to
AMP Incorporated, Harrisburg, Pa.

Filed Sept. 21, 1967, Ser. No. 8,683

Term of patent 14 years

(Cl. D26—1)

FIGURE 1 is a perspective view of an electrical connector;

FIGURE 2 is a top plan view thereof;

FIGURE 3 is a front elevational view thereof;

FIGURE 4 is a side elevational view thereof;

FIGURE 5 is a view taken along lines 5—5 of FIGURE 4; and

FIGURE 6 is a bottom plan view thereof.

The dominant features of my design reside in the portions shown in full lines.

I claim:

The ornamental design for an electrical terminal, substantially as shown and described.
